UNITED STATES PATENT OFFICE.

JOSEPH DOBRODENKA AND FRANK DOBRODENKA, OF MILWAUKEE,
WISCONSIN.

EXTENSION-TABLE.

SPECIFICATION forming part of Letters Patent No. 757,544, dated April 19, 1904.

Application filed December 19, 1903. Serial No. 185,773. (No model.)

To all whom it may concern:

Be it known that we, JOSEPH DOBRODENKA and FRANK DOBRODENKA, citizens of the United States, and residents of Milwaukee, in the county of Milwaukee and State of Wisconsin, have invented certain new and useful Improvements in Extension-Tables; and we do hereby declare that the following is a full, clear, and exact description thereof.

Our invention relates to extension-tables, each of which comprises two leaves independently movable, with legs and slides to be pushed beneath the table-top or drawn out and secured level with the same, said invention consisting in certain peculiarities of construction and combination of parts hereinafter particularly set forth with reference to the accompanying drawings, and subsequently claimed.

Figure 1 of the drawings represents a plan view of an extension-table in accordance with our invention as it appears when the two leaves of same are drawn out and the top removed; Fig. 2, a vertical longitudinal section view of a fragment of the table central of the same, one of the leaves being drawn out and the top canted; Fig. 3, a transverse section view indicated by lines 3 3 in the second figure, and Figs. 4, 5, and 6 are illustrations of details of latch mechanism embodied in said table.

Referring by letter to the drawings, A indicates a rectangular frame, and in practice this frame is supported on suitable legs. Rigidly connected to the frame A are upwardly-extending side bars B, and likewise connected to said frame adjacent to each of the side bars are oppositely-inclined tracks C D, each provided with an upper tongue b, engaging a groove c in a slide E, to which a table-leaf F is fastened, there being two leaves and two slides for each leaf.

Stop-blocks d are made fast in upper notches of brackets G, rigid on the frame A, and said blocks engage lateral grooves e in the slides aforesaid to limit outward movement of the same, their inward movement being limited by other stop-blocks f, depending from a longitudinally-slotted cross-piece H in rigid connection with the side bars B midway of the extremities of same.

Engaging the slot g in the cross-piece H is 50 a batten I, fast to the under side of the table-top J, this top being removable to permit of access to other parts of the table.

To facilitate the movement of the slides E on their tracks C D, antifriction-rollers h are 55 arranged in connection with said tracks adjacent to their outer ends and engage the grooves c in said slides.

In depending rigid connection with the under side of each of the table-leaves F, to project inward from the same, is a bracket K, this bracket being slotted to serve as a guide for a carrier L, in which a roller i is mounted. The carrier is pivotally connected to an arm of a bell-crank lever M, hung between 60 bracket-arms, and this lever has a hook extension j for engagement with a keeper k in depending connection with the table-top batten I, longitudinally of the same. The other arm of the bell-crank lever is connected to the 70 inner end of a link N, the outer end of the link being at a right angle to the remainder and provided with an aperture, whereby it serves as a bearing for a rod P, that is guided in apertures provided in plates n p, attached 75 to the inner and outer sides of an end bar Q, depending from the table-leaf. A spiral spring q is arranged on the rod P between its guides m n, and said rod is provided with notches r r' at right angles to each other. 80

Guided on the angular shank s of a button set in a recess of the table-leaf end bar forward of the guide-plate n thereon is a longitudinally-slotted latch S under a spring m, this latch being for engagement with the 85 notches in the rod P, and a handle t is shown in pivotal connection with the outer end of said rod. To limit turning of the rod in either direction, the inner end of the same has a bent pin u set therein to strike at either end 90 against the link N aforesaid.

The cross-piece H aforesaid is provided with central notches v to obtain clearance for the rollers i, and recesses w are provided in the under side of the table-top J for the same 95 purpose.

The table-leaves F and parts in connection therewith being pushed beneath the table-top

J, each spring-controlled rod P is turned to disengage its notch r' from the latch S, and expansion of the spring q on said rod causes the latter and the link N therewith to swing the 5 corresponding bell-crank lever M and depress the roller-carrier L, connected thereto, while at the same time the hook extension j of said lever is caught in the keeper k, depending from the under side of the table-top, and the 10 notch r of the aforesaid rod engaged by said latch. Hence the table-leaves and parts therewith are locked in the adjustment beneath the table-top.

To draw out a table-leaf, the rod P there- 15 with is manipulated the reverse of what is above explained to unlock said leaf and cant the table-top, this canting operation being the result of a lift of a roller i, that bears against the under side of said table-top when said ta- 20 ble-leaf and parts therewith are drawn out, whereby the friction that would otherwise result is eliminated. The table-leaf being drawn out, the rod P therewith is manipulated to lower the roller i, opposing the table-top, and 25 this top is then level with said leaf, the canted and normal position of said top being shown by full and dotted lines in Fig. 2.

When the leaves F are pushed beneath the top J, the side and bars B Q abut to inclose 30 the tracks, slides, and other parts of the table, and blocks α may be used, in connection with the depending batten I of the table-top, to prevent said top from being displaced.

Having thus described our invention, what 35 we claim as new, and desire to secure by Letters Patent, is—

1. An extension-table comprising a frame provided with upwardly-extending side bars and oppositely-inclined tracks, slides on the 40 tracks, leaves fast on the slides, end bars and brackets depending from the leaves, carriers guided in the brackets, antifriction-rollers mounted in the carriers, bell-crank levers in connection with said carriers and provided 45 with hook extensions, spring-controlled pull-

rods extending through said end bars, links connecting said levers and the pull-rods, spring-controlled latches arranged in conjunction with the end bars to engage notches at right angles to each other in said rods, a slot- 50 ed cross-piece fast on said side bars midway of their extremities and provided with notches normally engaged by said rollers, a top having a depending batten loose in the cross-piece slot, a keeper depending from said batten for 55 the engagement of the hook extensions of the aforesaid levers, and means for limiting play of said slides.

2. An extension-table comprising a frame provided with upwardly-extending side bars 60 and oppositely-inclined tracks, slides on the track, leaves fast on the slides, end bars and brackets depending from the leaves, having carriers guided in the brackets, antifriction-rollers mounted in the carriers, bell-crank levers in connection with said carriers and provided with hook extensions, spring-controlled pull-rods extending through said end bars, links connecting said levers and the pull-rods, stops extending from said rods to come into 65 contact with the links, spring-controlled latches arranged in the end bars to engage notches at right angles to each other in the aforesaid rods, a slotted cross-piece fast on said side bars midway of their extremities and 70 provided with notches normally engaged by said rollers, a top having a depending batten loose in the cross-piece slot, a keeper depending from said batten for the engagement of 75 the hook extensions of the aforesaid levers, and means for limiting play of said slides.

In testimony that we claim the foregoing we have hereunto set our hands, at Milwaukee, in the county of Milwaukee and State of Wisconsin, in the presence of two witnesses.

JOSEPH DOBRODENKA.
FRANK DOBRODENKA.
